(57) **CLAIM**

The ornamental design for a display screen with graphical user interface for funds transfer, as shown and described.

DESCRIPTION

FIG. 1 depicts a view of a design for a display screen with graphical user interface for funds transfer, in accordance with an embodiment; and,

FIG. 2 depicts a view of the design, in accordance with another embodiment.

The outermost broken line drawings of the display screen and all other broken line drawings of the images, text, and other elements are included for the purpose of illustrating portions of the article and form no part of the claimed design.

1 Claim, 2 Drawing Sheets

Transfers

Accept Transfer to Your Email Address or Mobile Number

Did you receive a transfer notice from someone you know? You can complete this transaction and collect the money by setting up your email address or mobile phone number to accept transfers. Please enter the confirmation number from your transfer notice and select Verify Email or Mobile to continue.

* = required

* Enter your confirmation number:

By checking this box, I confirm that I:

a) have read and agree to the terms of the service agreement, including the terms of the Email/Mobile Network Transfers section;
b) consent to receive email and automated text messages about Email/Mobile Transfers;
c) will only register mobile numbers where I am the account holder, or I am not the account holder, I have the account holder's permission to register that mobile number; and
d) will obtain the consent of the person to whom I want to send a Mobile Transfer text message to receive the automated text message.

I Agree I Don't Agree

Enter your confirmation number.

By checking this box, I confirm that I:

a) have read and agree to the terms of the service agreement, including the terms of the Email/Mobile Network Transfers sections;

b) consent to receive email and automated text messages about Email/Mobile Transfers;

b) will only register mobile numbers where I am the account holder, or I am not the account holder, I have the account holder's permission to register that mobile number; and

d) will obtain the consent of the person to whom I want to send a Mobile Transfer text message to receive the automated text message.

I Agree I Don't Agree

FIGURE 1

Did you receive a transfer notice from someone you know? You can complete this transaction and collect the money by setting up your email address or mobile phone number to accept transfers. Please enter the confirmation number from your transfer notice and select Verify Email or Mobile to continue.
